HAND BAG

Filed Jan. 25, 1930

UNITED STATES PATENT OFFICE

MORRIS E. LESSIN, OF NEW YORK, N. Y., ASSIGNOR TO MAURICE LEVY, OF NEW YORK, N. Y.

HAND BAG

Application filed January 25, 1930. Serial No. 423,290.

My invention relates to a new and improved handbag.

One of the objects of my invention is to provide a new and improved handbag and 5 supplemental container.

Another object of my invention is to provide an improved handbag provided with a frame to which a supplemental container is connected.

10 Another object of my invention is to provide a handbag of this type in which the supplemental container is movably mounted within the handbag so that said supplemental container can remain concealed until it is 15 moved into operative position.

Another object of my invention is to provide a handbag provided with frame members hinged to each other, one of said frame members having a depending casing in which 20 a supplemental container is movably mounted.

Another object of my invention is to provide a handbag of this type in which the supplemental container is moved into operative 25 position by means of a spring, when a suitable latch is manually released.

Other objects of my invention will be set forth in the following description and drawing which illustrate a preferred embodiment 30 thereof, it being understood that the above general statement of the objects of my invention is intended merely to generally explain the same and not to limit it in any manner.

Fig. 1 is a front elevation showing the improved handbag, part of the material of said handbag being cut away in order to more clearly illustrate the supplemental parts.

Fig. 2 is a top view.

40 Fig. 3 is a detail elevation partially in section showing the supplemental container and the casing therefor.

Fig. 4 is a sectional view on the line 4—4 of Fig. 1.

45 Fig. 5 is a detail view partially in section showing the container in its outer or operative position.

Fig. 6 is a top view partially in section showing the latch which holds the supplemental container in position.

Fig. 7 is a sectional view on the line 7—7 of Fig. 1.

The device comprises an ordinary handbag L comprising frame members 10 of any suitable construction, to which any suitable material is connected in the well known manner. The invention does not depend upon and it is not limited to any particular type of handbag, frame, or covering material, and it is 55 not limited to handbags.

The two frame members 10 are kept in closed position by means of a catch C which may be of any suitable type. For example, such catch may be of the well known type which is hinged to one of the frame members 10. One of the frame members 10 is provided with a casing 13 which downwardly and laterally projects therefrom. The casing 13 may be integral with the respective frame member 10, or said casing 13 may be made separate from its frame member 10, the two parts being connected in any suitable manner. The supplemental container 12 is slidably mounted within the casing 13. 60 65 70 75

For convenience of description, it may be assumed that the parts are held in the vertical position illustrated in Fig. 1, although of course the operation is the same if the device is held in any other position.

As shown in Fig. 5, for example, the bottom of the casing 13 is provided with a blade spring 18 suitably connected to the bottom thereof, and the free ends of said blade spring 18 upwardly force the supplemental container 12 into the outer or operative position shown in Fig. 5. The bottom of the container 13 is provided with a slidable channel member 14 in which the free ends of the blade spring 18 are guided. The supplemental container 12 may be connected to the channel 14 by means of a hinge 19 so that when the channel 14 is in its upper position, the container 12 may be turned back to the horizontal position, as shown in Fig. 4. The supplemental container 12 is then mounted in the horizontal position because it rests against the adjacent frame member 10. The top of the casing 13 is provided with a flange as 80 85 90 95 100 shown in Fig. 5, so that the blade spring 18

cannot force the channel 14 out of said casing 13. The supplemental container 12 may be provided with a cover 12a connected thereto by means of a suitable hinge with which a 5 spring may be associated so that when the supplemental container 12 is moved to its outer position, it can turn back to the horizontal position illustrated in Fig. 4, and the cover 12a will automatically open. The cover 10 12a will then be held in the inclined position shown by the dotted lines in Fig. 4, so that convenient access may be had to the contents of the supplemental container 12. In this particular embodiment, said supplemental 15 container 12 serves as a vanity case to hold cakes of cosmetic, such as powder and rouge. However, the device may also contain powder puffs, and it may be used for any other purpose.

20 The bottom of the cover 12a is provided with a locking projection 17, and this enters a suitable recess in the corresponding frame member 10, when the supplemental container 12 is moved to the inoperative position shown 25 in full lines in Fig. 4. A latch member 15 is slidably mounted so as to engage said locking member 17, the latch member 15 being actuated to the operative position by means of a spring 20. The latch member 15 is provided 30 with an exterior portion which can be manipulated by the thumb of the user, and it slides in slot 21.

Hence, the device can be used as an ordinary handbag. If it is desired to utilize the 35 supplemental container 12, it is merely necessary to slide the latch member 15 to the inoperative position against the force of the tension spring 20. The ends of the blade spring 18 then automatically force the supplemental container 12 upwardly, so that the parts assume the dotted line position shown 40 in Fig. 4.

While I prefer to utilize a spring member 45 to automatically force the supplemental container into the outer position, this is not necessary and my invention is not to be limited thereto.

Numerous other changes and omissions 50 could be made without departing from the spirit of the invention, as I claim that the invention is pioneer to the extent that it provides a supplemental container movably connected to the frame of a bag, said supplemental container being substantially concealed from view when it is in the inoperative position.

For example, it would not be departing 60 from the invention if the supplemental container were movably connected to the outer frame by being removably connected to said frame. This would still make the device extremely convenient because the supplemental container, such as a vanity case, would be conveniently held on the frame of the bag, separated from the other contents of the bag.

The frame members 10 are provided with the usual U-shaped channels in which the fabric or other covering can be suitably clamped. This U-shaped channel extends 70 around the lateral walls and the outer wall of the casing 13, so that the fabric can be suitably clamped in position around said casing in order to conceal the same. Hence, the improved handbag looks like any ordinary handbag, save for the slight bulge produced 75 by the casing 13.

It will also be noted that the depth of the casing is greater than its width so that the supplemental container is held connected to the frame in such position as to produce a 80 minimum departure from the ordinary appearance of a handbag. If the supplemental container were not held in the depending position illustrated herein, the mouth of the handbag would be objectionably enlarged. 85

I have shown a preferred embodiment of my invention, but it is clear that numerous changes and omissions can be made without departing from its spirit.

90 While I have shown the supplemental container mounted in a casing, it is not necessary to utilize a closed casing as any suitable guide could be substituted for a casing, as an equivalent thereof.

Likewise, any suitable stop could be used 95 in order to prevent the ejection of the container 12 from the casing 13, as this would be an equivalent for the flange formed at the outer mouth of the casing 13.

100 I claim:

1. In combination, a handbag having an outer frame, a casing connected to the frame, a slide mounted in said casing, and a supplemental container hinged to said slide.

105 2. In combination, a handbag having an outer frame, a casing connected to the frame, a slide mounted in said casing, and a supplemental container hinged to said slide, and spring means located in said casing and adapted to outwardly move said slide, the outer end of said casing having means adapted to prevent the ejection of said slide.

110 3. In combination, a handbag having a frame, a casing connected to said frame, a slide located in said casing, spring means located in said casing and adapted to outwardly move said slide, said casing having means at the outer end thereof to prevent the ejection of said slide, a supplemental container hinged to said slide and adapted to fit within 115 said casing, and a cover hinged to said supplemental container, said cover having a spring adapted to automatically force the same to the open position, said supplemental container being adapted to rest upon the adjacent portion of the frame when it is moved to the outer position.

120 4. In combination, a handbag having a frame, a casing connected to said frame, a slide located in said casing, spring means lo- 125

cated in said casing and adapted to outwardly move said slide, said casing having means at the outer end thereof to prevent the ejection of said slide, a supplemental container hinged to said slide and adapted to fit within said casing, and a cover hinged to said supplemental container, said supplemental container being adapted to rest upon the adjacent portion of the frame when it is moved to the outer position.

5. In combination, a handbag frame having a casing, a slide mounted in said casing, spring means in said casing and adapted to move said slide to the outer position, a supplemental container hinged to said slide, said supplemental container being adapted to fit within said casing, and cooperating latch means associated with said frame and with said supplemental container to hold said supplemental container within said casing.

6. In combination, a handbag having a frame, a casing connected to said frame, a slide located in said casing, spring means located in said casing and adapted to move said slide to the outer position, said casing having means at the outer end thereof to prevent the ejection of said slide, a supplemental container hinged to said slide, a cover hinged to said supplemental container, said cover having a projection at its inner end, and a latch connected to said frame and adapted to engage said projection, in order to hold said supplemental container within said casing.

35 In testimony whereof I affix my signature.
MORRIS E. LESSIN.
